(57) **CLAIM**

I claim the ornamental design for a coffee cup, as shown and described.

DESCRIPTION

FIG. 1 is a top, front perspective view of a first embodiment of a coffee cup;

FIG. 2 is a top, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a top, front perspective view of a second embodiment of a coffee cup;

FIG. 10 is a top, rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.
